UNITED STATES PATENT OFFICE.

WILLIAM H. NEWELL, OF PHILADELPHIA, PENNSYLVANIA.

SECRET SUPPLY, WASTE, AND OVERFLOW FOR BASINS AND BATHS.

SPECIFICATION forming part of Letters Patent No. 399,691, dated March 19, 1889.

Application filed May 22, 1888. Serial No. 274,663. (No model.)

To all whom it may concern:

Be it known that I, WILLIAM H. NEWELL, a citizen of the United States, residing in the city and county of Philadelphia, State of Pennsylvania, have invented a new and useful Improvement in Secret Supply, Waste, and Overflow for Basins and Baths, which improvement is fully set forth in the following specification and accompanying drawings.

10 My invention consists of novel features in secret supply, the waste, and overflow for a basin or bath, as will be hereinafter set forth, and each feature definitely claimed.

Figure 1 represents a face view of a device embodying my invention. Fig. 2 represents a central vertical section thereof, the valve being open.

Similar letters of reference indicate corresponding parts in the two figures.

20 Referring to the drawings, A represents a hollow stand or column having within the same, near the lower end thereof, an inclined seat, a, on which rides the inclined bottom edge, b, of the valve B, which is mounted with 25 the tube C, the latter being within the stand A, and having openings D, located at or about the level of the overflow-openings E of the stand A. The nozzle F joins the confluent pipes G H, the latter being adapted for hot 30 and cold water and provided with cocks J, whose handles K are adjacent to the handle L of the tube C.

It will be noticed that the inner end of the nozzle F passes through the perforated cap or 35 strainer plate M of the overflow-collar E, and is screwed to the outlet branch N of the confluent pipes G H.

The operation is as follows: Water, hot or cold, or both, is turned on by the cocks J and 40 enters the basin or bath-tub through the nozzle F. As the water rises, it fills the stand, and when it reaches the openings D of the tube C it overflows therethrough, the water entering the collar E also overflowing through 45 the said openings. When the water is turned off, the stand A is rotated, whereby, owing to the inclined seats a b, said stand rises, thus lifting the valve B with it and permitting the escape of the water through the foot-pipe P.

50 When the basin or tub is cleared, the stand is again rotated, whereby it rides down, its

bottom seat and the valve closes. Should the supply of water continue while the valve is closed, it will enter the collar E and overflow through the openings D into the tube C, and so reach the foot or discharge pipe P. The ascent of the tube C, and consequent opening of the valve B, is limited by pins c d, which are secured, respectively, to the bottom of the valve and base of the valve-chamber, the pin c being vertical and the pin d horizontal, the former abutting against the latter when the valve is raised to a predetermined height and acting as a stop to the motion thereof.

Having thus described my invention, what I 65 claim as new, and desire to secure by Letters Patent, is—

1. A basin, in combination with a hollow stand or column having overflow-openings, a tube within said column, having openings corresponding to the overflow-openings of the stand, a nozzle leading from said overflow-openings, supply-pipes leading into said nozzle, and a pipe leading from said basin to said column, substantially as and for the purpose set forth.

2. A stand having an overflow-collar, a valve and a supply-pipe, and a nozzle which passes through the covering cap or strainer of said collar and is connected with said supply-pipe, 80 said parts being combined and operating substantially as described.

3. The confluent supply-pipes united at the overflow-collar of the stand and connected with a discharge-nozzle which passes through 85 the strainer of said collar, substantially as described.

4. The combination of a basin with a stand-pipe having a valve-seat in the lower part thereof, an outlet-pipe and overflow-openings 90 in the top, a tube within said stand-pipe having overflow-openings, a valve seated on said seat in the lower part of the stand-pipe, confluent pipes leading from said overflow-openings to a nozzle discharging within the basin, 95 and a pipe connecting said basin and stand-pipe, substantially as described.

WM. H. NEWELL.
